(57) **CLAIM**

The ornamental design for a boot as shown and described.

DESCRIPTION

FIG. 1 is perspective view of a boot showing my new design.

FIG. 2 is a right-side view thereof.

FIG. 3 is a left-side view thereof.

FIG. 4 is a front view thereof.

FIG. 5 is a rear view thereof.

FIG. 6 is a top view thereof; and,

FIG. 7 is a bottom view thereof.

The broken lines shown on the shaded portions of the boot depict stitching, which forms no part of the claimed design. The broken lines showing the remainder of the boot show portions that form no part of the claimed design.

1 Claim, 7 Drawing Sheets
